UNITED STATES PATENT OFFICE.

LEWIS E. PAGE AND CHARLES W. ANDREWS, OF ALLENTEWON, NEW YORK.

AUGER-HANDLE.

SPECIFICATION forming part of Letters Patent No. 416,420, dated December 3, 1889.

Application filed August 2, 1888. Serial No. 281,834. (No model.)

To all whom it may concern:

Be it known that we, LEWIS E. PAGE and CHARLES W. ANDREWS, citizens of the United States, residing at Allentown, county of Allegheny, and State of New York, have invented certain new and useful Improvements in Auger-Handles; and we do hereby declare that the following is a full, clear, and exact description of the invention.

10 Our invention consists of an improved auger-handle, the mechanism being so arranged as to hold augers or bits of any size straight and firm in the handle by a combined wedge, screw, and lever power, as illustrated in the accompanying drawings—

Figure 1 is a side elevation of our new and improved auger-handle. Fig. 2 is a similar view, partly in section, showing the interior mechanism. Fig. 3 is a transverse longitudinal sectional view taken on line $x-x$ of Fig. 1; and Fig. 4 is a detail view of the plate H , hereinafter described.

The same letters of reference indicate corresponding parts in all the figures.

25 Referring to the several parts by letter, the metal frame of the handle is flat on both sides of its middle part A and terminates in the long round opposite sockets $A'A'$. The upper part of the middle frame A curves up 30 in an oval form or concave A^2 , having on top the central collar or turret B , formed with an internal screw-thread b .

In the handle A are pivoted near their centers on transverse screw-pivots $E E$ the semicircular clamps $D D$, the lower ends or jaws of which are formed on their inner faces with a series of teeth D' .

35 Between the clamps D is formed in the handle A the stationary clamp-socket F , the inner faces of which are inclined, as shown.

C indicates the clamping-screw, which works through the threaded turret B , having the plain conical lower inner end C' .

40 The augers or bits are placed in the handle, and as the faces of the shank-socket F are inclined, the space between them being wedge-shaped, they will fit any-sized auger-shank. The clamping-screw C is then screwed down,

when its conical inner end forces the upper ends of the pivoted clamps $D D$ apart, closing their lower serrated jaws firmly on the bit or auger shank. It will be seen that the clamps $D D$, owing to their semicircular shape, will, when the clamping-screw is screwed down to open their upper ends, close with a rotary motion on the bit or auger shank, causing it to fit any-sized auger or bit and giving them a lever-power when working in conjunction with the screw-and-wedge power. The clamps $D D$ working on the outside of the stationary socket-piece F , it will be seen that these stationary sockets relieve the pivoted clamps from the twisting strain which would otherwise fall upon them, and that the screw, wedge, and lever powers combined will hold the auger and bit straight and firmly in place.

H indicates a slotted frame-plate, which is held by screws $h h$ at the bottom of part A of the handle, by removing which and taking out the screw-pivots $E E$ the clamps $D D$ can be readily removed from the handle.

Having thus described our invention, what we claim, and desire to secure by Letters Patent, is—

1. The combination of the hollow handle formed with the stationary socket F , having the inclined inner faces and the threaded turret B , the semicircular clamps centrally pivoted in the handle, and the clamping-screw C , having the conical lower end, substantially as set forth.

2. The combination of the hollow handle having the stationary socket F , having the inclined inner faces, the threaded turret B , the screw-pivots $E E$, and the removable frame-plate H , the semicircular clamps centrally pivoted on the screw-pivots $E E$, and the clamping-screw C , having the conical lower end, substantially as set forth.

LEWIS E. PAGE.
C. W. ANDREWS.
